CLAIM

The ornamental design for a monitor television receiver, as shown and described.

DESCRIPTION

FIG. 1 is a perspective view of a first embodiment of a monitor television receiver showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear plan view thereof.

FIG. 8 is another perspective view thereof wherein the earphone portions are in the using condition. The earphone portions in broken lines are for illustrative purpose only and forms no part of the claimed design.

FIG. 9 is a perspective view of a second embodiment of a monitor television receiver showing my new design in the using condition;

FIG. 10 is a top plan view thereof;

FIG. 11 is a left side elevational view thereof;

FIG. 12 is a front elevational view thereof;

FIG. 13 is a bottom plan view thereof;

FIG. 14 is a right side elevational view thereof; and

FIG. 15 is a rear plan view thereof; and,

FIG. 16 is another perspective view thereof, wherein the earphone portions are in the using condition.
